HANDBAG CLOSURE CLASP

David Damast, 522 Shore Road,
Long Beach, N.Y. 11561

Filed May 7, 1968, Ser. No. 11,826

Term of patent 3½ years

Int. Cl. D8—03

U.S. Cl. D87—2

Fig. 5

FIG. 1 is an exploded perspective view of a handbag closure clasp showing my new design;

FIG. 2 is an assembled top plan view;

FIG. 3 is an assembled front elevational view, the opposite side being substantially flat and unornamented; and

FIG. 4 is a side elevational view thereof.

I claim:

The ornamental design for a handbag closure clasp, substantially as shown and described.
